AWNING

Christian E. Skyum, Chicago, Ill.

Application August 18, 1938, Serial No. 225,515

5 Claims. (Cl. 156—42)

The invention relates to awnings.

One object of the invention is to provide an awning-structure which is provided with locking-means for locking the pivoted frame to which the lower portion of the awning is attached, so that it will be impossible for wind-pressure to lift the frame or awning from below. Heretofore, it has been customary to provide a heavy frame and curtain and to depend upon their weight to hold them down against upward wind-pressure. With said locking-means it is possible to use a material which is light in weight and a light frame, which can be easily raised by manual force. The locking-device automatically secures the frame in its lowered position and the lifting connection is adapted, when manipulated automatically to release the locking-device.

Other objects of the invention will be apparent from the following detailed description.

The invention consists in the several novel features which are hereinafter set forth and are more particularly defined by claims at the conclusion hereof.

In the drawing: Fig. 1 is a perspective of an awning embodying the invention. Fig. 2 is a detail of one of the automatic locking-devices for the pivoted frame. Fig. 3 is a plan of the parts shown in Fig. 2, parts being shown in section. Fig. 4 is a perspective of two of the sheaves for guiding the lifting and lowering-cords. Fig. 5 is a section through the guide for directing the pull-cord from the inside to the outside of the building. Fig. 6 is a section on line 6—6 of Fig. 5. Fig. 7 is a perspective of the inner sleeve of the cord-guide which carries the outer guide-sheave shown in Fig. 5. Fig. 8 is a perspective of the thimble which carries the outer sleeve in said cord-guide. Fig. 9 is a perspective of a portion of the outer sleeve of said cord-guide.

The invention is exemplified in a structure which comprises a supporting-frame having stiles 15, the upper ends of which are fixedly connected together by a cross-bar 16. The stiles and bar may be formed of channeled or angle-iron stock. This frame is adapted to fit against or be secured in the usual window-frame. A pivoted frame comprises side-members 17 which are pivoted at 18 in lugs 18^a fixed to the stiles, and a cross-bar 19 to which the outer ends of bars 17 are rigidly secured.

The curtain is formed of a suitable light fabric and comprises a portion *a* which extends between the fixed frame-bar 16 and cross-bar 19 of the pivoted frame and sides *a'* adapted, when the pivoted frame is lowered, to close the triangular spaces at the sides of the fixed and pivoted frames. The upper end of the curtain is secured around a rod 22 which extends through ears 23 on the fixed frame-bar 16 and the other end of said curtain is connected to a rod 24 which is held

on ears 25 on the swinging-frame. The inner lower corners of the curtain-sides are suitably attached to wires 26 which are fixed on stiles 15.

The swinging frame 17, 19 is supported in its lowered position by a pair of braces 32 which are respectively pivoted to the stiles at 33, and studs 34 which are fixed in side-bars 17, respectively, and extend through inwardly extending open-ended slots 35 in the outer and lower portions of the braces. A latch 36 is pivoted on each of the studs 34 and is bifurcated to extend around the lower end of one of the braces. Each latch 36 is provided with a cross-wall 37 which is adapted to fit into a notch 38 in the outer end of brace 32. The latch comprises a downwardly extending arm 39 which serves as a weight for causing the wall 37 to enter the notch 38 when the swinging-frame is lowered, and also has a means for connection to the latch-operating cord. When the latch is raised, as indicated by dotted lines in Fig. 2, cross-walls 37 will be disengaged from notches 38 so that the latches will be released so they can swing upwardly with the swinging-frame. When the swinging-frame is lowered, the latches will drop by gravity so their cross-walls 37 will enter the notches 38 and lock braces 32 against upwardly swinging movement and thereby correspondingly lock the swinging frame 17, 19.

In order to make it possible to raise the curtain and swinging-frame with slight manual force, springs are applied to partially counter-balance the weight of the swinging-frame and the curtain. For this purpose, a torsion spring 26 is coiled around each pivot-stud 18. One end 27 of each spring is extended through one of the side-bars 17 of the swinging-frame and the other end 29 is held in a notched disk 28 which is fixedly secured to the lug 18^a in which pivot-stud is secured. Disk 28 has a flange with notches 30 in circumferential series so that the force of the spring may be adjusted. The use of braces 32 for preventing the upward swing of the frame, makes it possible to use spring-pressure to assist in lifting the frame and curtain.

A cord-system for raising and lowering the awning comprises a cord-pull 41 which is located inside of the window and is guided around a sheave 42 at the inside of the window-frame, and a sheave 43 adjacent the outside of the window-frame. Cord 41 is connected to a runner 44. Two cords 45, 46, each connected to runner 44 and to ears 47 at the corners of the swinging-frame 17, 19, respectively, are adapted to lift the frame and curtain. Cord 45 is extended around a sheave 48 in a pulley-block 49 which is pivotally supported from bar 16. From sheave 48, cord 45 passes around a sheave in pulley-block 51 which is pivotally suspended from fixed frame-bar 16 at one side of the curtain. Cord 46 lifts the other side of the pivoted frame, and extends around a

sheave in a pulley-block 52 which is pivotally suspended from bar 16. From block 52, cord 46 passes to an ear 53 which is fixed to the pivoted frame near one of its front corners. Runner 44 is guided on the reach of cord 45 between pulley-block 49 and pulley-block 51.

The latches 36 are released by a pull on the cord 41 through a cord 54 which is connected to runner 44, passes around a second sheave in pulley-block 49, and around a sheave in a pulley-block 55 which is pivotally suspended from the central portion of fixed frame-bar 16. From pulley-block 55, cord 54 is provided with branches 56, which lead to the latches, respectively. Each branch passes around a sheave in a pulley-block 57 to a sheave in a pivoted pulley-block 58, and thence to one of the latches 39. Blocks 57, 58 are pivotally connected to the pivoted frame.

Sheaves 42, 43 for pull-cord 41 are mounted in a tubular guide which is adapted to extend through the window-frame or wall of a building, and comprises an outer sleeve 60 which fits into a hole bored through the frame. A cap 61 on the inner end of sleeve 60 is provided with an opening for cord 41. An inner sleeve 62 fits in the sleeve 60 and is provided at its front end with a fixed cap 63 which has an opening in one side for the reach of cord 41 between sheave 43 and runner 44. A tongue 64 is formed on outer sleeve 60 and fits in a slot 65 in sleeve 62 to hold the sleeves against relative rotation. Sheave 43 is mounted in a thimble 66 which is provided with a tongue 67 which extends through slot 65 in sleeve 62 and which is engaged by tongue 64 so that the thimble will also be secured against rotation and axial movement relatively to the sleeves, and in the outer end of sleeve 62. This exemplifies a simple guide which may be readily installed for guiding the operating cord from the inside to the outside of the window.

The operation will be as follows: assuming the awning to be lowered, there will be sufficient slack in the cords 45, 46 so that when the operator pulls the cord 41 the runner 44 will first operate the cord 54 a predetermined distance, which is sufficient to operate branches 56 of cord 54 to swing the latches 36 into the lower dotted position shown in Fig. 2. As soon as the latches 36 have been released, the slack in the cords 45, 46 will be taken up and there will be substantially equal tension on cords 45, 46 and 54. Upon continued pull on cord 41, cords 45, 46 will swing the bail 17, 19 upwardly and raise the curtain. The cord 41 may be secured to hold the frame raised in any suitable manner. When the latches 39 are released the swinging-frame 17, 19 will be released by braces 32, so the studs 34 can pass out of slots 35 and during the remainder of the lifting movement, the lower edges of brace-members 32 will ride on studs 34. During the lowering of the swinging-frame, which occurs when the cord 41 is released, the studs 34 will re-enter slots 35 and limit the downward swinging of the frame. As soon as the cord 41 is released, latches 39 will drop by gravity so their cross-walls 37 will enter notches 38 and lock the braces 32 to the sides 17 of the swinging-frame and thereby lock said frame against upward movement. Springs 26 assist the operator in lifting the awning so little manual force is required.

The invention exemplifies an awning which comprises a swinging-frame and latches for locking the frame against upward movement by wind-pressure and which are automatically released by

the lifting device and automatically become effective when the frame is lowered.

The invention is not to be understood as restricted to the details set forth, since these may be modified within the scope of the appended claims, without departing from the spirit and scope of the invention.

Having thus described the invention, what I claim as new and desire to secure by Letters

10 Patent is:

1. The combination with an awning structure comprising a bail pivoted to an awning support and braces for supporting the bail pivoted to the support, of latches pivoted to the side-bars of the bail and provided with means for engaging the braces and locking them against upward swinging movement, and stud-and-slot connections between the braces and the side-bars of the bail, the latches being adapted to secure the 15 studs against movement in the slots and to permit the studs to move in the slots.

2. The combination with an awning structure comprising a bail pivoted to an awning support and braces for supporting the bail pivoted to the support, of latches pivoted to the bail and provided with means for engaging the braces and locking them against upward swinging movement, and studs on the side-bars of the bail, the 25 braces being provided with slots through which the studs extend, the latches being adapted to lock the studs against movement in the slots and to permit the studs to move in the slots for swinging movement of the braces.

3. The combination with an awning structure comprising a bail pivoted to an awning support and braces for supporting the bail pivoted to the support, of latches provided with forked ends embracing the free ends of the braces, and pivoted to the side-bars of the bail and provided with 30 means extending across the free ends of and for engaging the braces and locking them against upward swinging movement, and stud-and-slot connections between the braces and the side-bars of the bail, the latches being adapted to secure the 35 studs against movement in the slots and to move in the slots to permit swinging movement of the braces.

4. The combination with an awning structure comprising a bail pivoted to an awning support and braces for supporting the bail pivoted to the support, of latches pivoted to the side-bars of the bail and provided with means for engaging the braces and locking them against swinging movement, and studs for pivotally connecting the latches to the side-bars of the bail, the braces being provided with open-ended slots through 50 which the studs extend and out of which they pass when the latches are disengaged from the braces to permit swinging movement of the bail.

5. The combination with an awning structure comprising a bail pivoted to an awning support and braces for supporting the bail pivoted to the support, of latches pivoted to the side-bars of the bail and provided with means for engaging the braces and locking them against swinging movement, studs on the side-bars of the bail, the braces being provided at their free ends with notches adapted to receive the engaging means on the latches, and with slots through which the 55 studs extend for permitting swinging movement of the braces when the locking means on the latches are swung to release the braces.
